AUTOMATIC CURRENT REGULATOR

Willard M. Grimes, Jr., Wayne, N.J., assignor to Westinghouse Electric Corporation, East Pittsburgh, Pa., a corporation of Pennsylvania

Filed June 20, 1961, Ser. No. 118,389

5 Claims. (Cl. 13—1)

This invention relates to electrical circuits and particularly to automatic self regulating circuits wherein compensation for a disturbance or deviation in one part thereof will be immediately and automatically provided within another part whereby the current flow in such a circuit may be maintained at a substantially even level.

The object of the invention is to provide rapidly operating and extremely sensitive means which will narrow the very minute range of the effects of operation of such an automatic circuit so that the difference between maximum current and minimum current implied by the expression "substantially even" will be narrowed still further. Electrical regulator circuits in which means are employed in one part thereof to automatically compensate for any change in electrical characteristics in another part are conventional and all such circuits depend on a change to produce compensation. The present invention constitutes an improvement in the art in that the value of the desired compensation is made responsive not merely to the value of the disturbance or deviation for which compensation must be provided but to the rate at which the said disturbance or deviation takes place.

The present invention may be disclosed, by way of example, as an automatic current regulator for an electron bombardment tungsten zone refining furnace where it is particularly necessary that the current flow be maintained at a substantially even level. The means employed to produce compensation in the circuit to any disturbance or deviation in the current flow occurring in the furnace (including even a short circuit therein) is a non linear impedance element having a steeper slope in its current to voltage characteristic at the point fixed for the operating value than the slope of the simple linear current to voltage characteristic would indicate. With such an element provided in the supply circuit of such a furnace any change in impedance within the furnace will tend to produce a change in the current flowing therethrough and such change in current will produce a change in impedance value of the said element whereby the current will be maintained at a substantially even value. Since the said element has a nonlinear characteristic the disturbance or deviation will produce an exaggerated or amplified effect in the said impedance element with the result that the range of operation is materially narrowed, that is, the substantially even current value is more rigidly maintained.

Further, by way of example, a non linear impedance element may be provided in the form of tungsten filament lamps which are well known to have a steeply rising voltage current characteristic, that is a slope which is steeper than the slope of a simple linear relationship at a given point. Tungsten lamps have an advantage over ordinary resistors in that their incremental resistance $r_e = de/di$ is within their ordinary range of operation, always nearly twice the normal resistance $R = E/I$. The gain of a feedback loop is proportional to the incremental resistance, but the power lost in the current sensing resistor is proportional to the normal resistance. Hence the use of such a non linear element as current sensing device in a feedback loop enables nearly twice as much current regulating precision to be obtained for a given power loss.

2

A feature of the invention is a feedback loop having a load circuit, such by way of example, as an electron bombardment refining furnace, energized by a source of current having means independent of the said loop and compensating means in the form of a current sensing means having non linear characteristics whereby the gain of such loop is proportional to the incremental resistance thereof whereas the power lost in said sensing means is proportional to the normal or steady state resistance thereof.

Another feature of the present invention is the use of an amplifier tube having a non linear cathode resistor whereby the incremental change produced by some deviation elsewhere in the circuit and sensed by the said cathode resistor is changed by the amplification factor of the tube.

In accordance with one form of the invention, the cathode resistor is made comparatively great by using a number of tungsten filament lamps in series so that the desired effect of amplifying the response of the feedback resistor to a change is made by amplifying (by the amplification factor of the tube) a comparatively great magnitude. In accordance with another form of the invention, the cathode resistor of the amplifier tube consists of a second amplifier tube and its cathode resistor consisting in this case of one or more tungsten filament lamps in parallel. Consequently the gain of the second tube and its lesser magnitude cathode resistor is compounded by the first tube so that greater sensitivity may thus be achieved.

30 Other features will appear hereinafter.

The drawings consist of a single sheet have three figures, as follows:

FIG. 1 is a schematic circuit diagram showing a feedback loop including a single amplifier tube and a series of tungsten lamps used as a current sensing device;

35 FIG. 2 is a schematic circuit diagram of an alternative arrangement using a plurality of tungsten lamps in multiple and a plurality of tubes in the current path; and

FIG. 3 is a graph showing the characteristic current voltage relationship of a non linear resistor such as a tungsten lamp and the normal linear current voltage characteristic passing through the same desired fixed value at which the device is operated.

40 In the following description, certain values and certain specific types of apparatus are set forth as an aid to description and it is to be understood that these are merely by way of example and are not to be regarded as any limitation to the present invention.

45 The circuits shown in FIG. 1 and FIG. 2 hold the current flowing through a conventional electrode gun type of tungsten zone refining furnace 1 to a preset value. The electron tube V1 in FIG. 1 and the tubes V2 and V3 in FIG. 2, which are controlled by means independent of the feedback loop, are employed to maintain a steady loop current while providing a high difference of potential across the elements of the electrode bombardment furnace and acting as amplifiers of the reaction of the current sensing resistor.

50 The current path may be traced from the high voltage plate supply 2, over the conductor 3, through the secondary of the transformer 4, the bombardment electrode 5, the tungsten rod 6 (slowly moved through the element 5) the resistance unit consisting of a series of tungsten filaments 55 and the amplifier tube V1, conductor 8 to the other terminal of transformer 7, the cathode and the anode of the power amplifier tube V1, conductor 8 to the other terminal of the power supply element 2. The current flow in this loop is adjusted by the potential applied to the grid of the tube V1 here shown as coming from a fixed voltage

supply 9 in combination with an adjustable voltage supply 10 interconnected in any convenient and conventional manner. The voltage of the unit 10 may be regulated by the use of an autotransformer 11 whereby the power supply to the transformer 12 may be changed by manual adjustment of the device 11. In like manner the output of the high voltage supply may be regulated by the use of an adjustable autotransformer 13 whereby the power supply to the transformer 14 may be changed by manual adjustment of the device 13.

In accordance with the present invention, the current in the loop is limited by a feedback resistor shown here as a series of lamps R1.1 to R1.15 inclusive. Any disturbance in the circuit, such by way of example, as a random increase in bombardment current, will tend to increase the voltage drop across this feedback resistance with the result that the said increase in current will be almost equalled and nullified. An important feature of the present invention is that the feedback resistance consists of tungsten filament lamps whereby the non linear resistance characteristics of this element greatly increases the sensitivity thereof and operates to narrow the margin in the variation in current value. Thus, substantially constant current may be maintained in the loop even during the occurrence of short circuits in the furnace while it is operating at high voltage, say by way of example, at 3000 volts across the bombardment gap. Under such extreme conditions, the regulators still control the current so that it does not exceed more than a few percent of the current flowing when such 3000 volt furnace is operating normally.

In the feedback circuit described, the feedback element consists of tungsten filament lamps which have an advantage over ordinary resistors in that their incremental resistance $re = de/di$ is always, in the zone of normal operation, nearly twice the normal resistance $R = E/I$. It may be noted in FIG. 3 that the tungsten lamp voltage current characteristic 20 is very much steeper, say at the point R, than the normal voltage current characteristic 21 passing through this same point.

In FIG. 2, where the furnace 1 and transformer 4 of FIG. 1 may be fitted at the line A—A (the 220 v. A.C. supply being assumed to be connected to the high voltage plate supply, the voltage supply 18, the voltage supply 19 and the transformer 4 in like manner to that shown in FIG. 1) the feedback resistance consists of one or more tungsten filament lamps 15, 16 and 17 connected in parallel and there are two power amplifier tubes V2 and V3 connected in series each of whose grids are controlled by a separate adjustable voltage supply 18 and 19 respectively. The advantage of the use of more than one electron tube in the feedback circuit will be pointed out hereinafter.

The gain of the feedback loop is proportional to the incremental resistance, but the power lost in the current sensing resistor is proportional to the normal resistance. Hence the use of a tungsten lamp as a current sensing resistance in a feedback loop enables nearly twice as much current regulating precision to be obtained for a given power loss.

FIG. 2 shows a circuit in which the high incremental resistance of the current sensing lamp is multiplied by the amplification factor of the tube V3. If re is the incremental resistance of the paralleled lamps 15, 16 and 17 and Δe_L is the increase in voltage across the lamps due to an increase in current Δi , then Δe_L is equal to the product $re\Delta i$. The increase in voltage across tube V3 is equal to the product $re\Delta i$ multiplied by μ , the amplification factor of the tube. The cathode voltage increase on tube V2 is equal to the sum of the increment Δe_L and Δe_3 (the incremental voltage increase across the tube V3). Since Δe_L equals $re\Delta i$, and Δe_3 equals $\mu\Delta e_L$, which equals $\mu re\Delta i$, then $\Delta e_L + \Delta e_3 = re(\mu+1)\Delta i$.

Since the grid of V2 is fixed, the input signal to V2 is the cathode voltage. The cathode voltage of V2 is the

sum of the voltage across the lamps (15, 16 and 17) plus the voltage across V3. This change in voltage, as shown above, is equal to $re(\mu+1)\Delta i$. This voltage change is multiplied by the amplification factor of V2 which may be also equal to μ , the amplification factor of V3. The total voltage change across the series circuit V2, V3 and the lamps is equal to the sum $\Delta e_L + e_2 + \Delta e_3$. The voltage Δe_2 is equal to $re(\mu+1)\Delta i\mu$. The voltage change $\Delta e_2 + e_L$ has already been shown to be $re(\mu+1)\Delta i$. Thus the total voltage change Δe_T developed by a small change in current, Δi , is $re(\mu+1)\Delta i + re(\mu+1)\Delta i\mu$. For a one ampere regulator, a typical value of re is 165 ohms and a typical value of μ is 50. Substituting in

$$\Delta e_T = re(\mu+1)\Delta i + re(\mu+1)\Delta i\mu$$

gives $165 \times 51\Delta i + 165 \times 51 \times 50\Delta i$ which substantially reduces to $8,400\Delta i + 420,000\Delta i$. Thus $428,400\Delta i$ is the total increment of voltage Δe_T that would be developed against an incremental increase in current Δi . Hence $\Delta e_T \geq 428,400\Delta i$.

If a furnace operating at 3000 volts shorts out, a change of voltage, Δe_T , of 3000 volts is impressed upon the remainder of the circuit, which is the series string V2, V3 and the lamps 15, 16 and 17.

$$\begin{aligned} \Delta e_T / 428,000 &\geq \Delta i \\ 300 / 428,000 &\geq \Delta i \\ \Delta i &\leq .007 \text{ ampere} \end{aligned}$$

The circuit configuration in FIG. 2 is therefore capable of controlling a three kilowatt furnace from a five kilowatt power supply so that even a short circuit in the furnace cannot drive the current to within $\frac{1}{10}$ percent above normal.

The circuit in FIG. 1 wastes more power in normal operation than does that in FIG. 2 for a given ability to regulate but is still useful and simple. In FIG. 1, sensitivity is obtained by building up re by adding several lamps in series. The incremental voltage increase across the series string of lamps R1.1 to R1.15 is $re\Delta i$. This increment of voltage is multiplied by the amplification factor, μ , of the tube V1. The incremental voltage $re\Delta i$ is added to the voltage $\mu re\Delta i$ developed across the tube. The voltage increment across the series of lamps, and the voltage increment across the tube V1, add up to a total incremental increase in voltage of $re(\mu+1)\Delta i$. In a one ampere regulator using a FIGURE 1 circuit configuration re is 165 ohms per lamp and 15 lamps given a dynamic resistance of 15 times 165 which equals 2480 ohms. However, the normal resistance is only 1340 ohms which at a current of one ampere dissipates 1340 watts in addition to the 1000 watts dissipated by the tube V1. Again, assuming an amplification factor of 50, the total incremental change for an incremental current change Δi , is $(15)(165)(50+1)\Delta i$, which yields $126,000\Delta i$ which is a little less than $\frac{1}{3}$ of the gain that would be realized using another tube instead of the 15 lamps. The additional tube of the FIG. 2 circuit consumes a kilowatt in plate dissipation, but this tube has a regulating effectiveness of $\mu+1$ or 51 lamps which would require $(51)(1)(89.2)$ or 4550 watts, over 4.5 6 times that dissipated by the tube.

It is to be noted from this comparison of the FIG. 1 circuit and the FIG. 2 circuit that each stage multiplies the dynamic resistance of the lamps by $\mu+1$. FIG. 1 is the equivalent of $(51)(15)$ or 765 ballast lamps in series with the furnace. Yet the FIG. 1 circuit consumes in normal plate dissipation $(15)(89.2) + 1000$ watts for a total of 2340 watts. This would be consumed by only 26 lamps so that it appears that the FIG. 1 circuit gives the ballasting effect of 765 lamps but requires the power for operating only 26.

The FIG. 2 circuit is even more spectacular in this respect. It has the regulating effectiveness of $(1)(51)$ which is equivalent to 2601 ballast lamps, yet con-

sumes in normal plate dissipation the equivalent power of only 23 lamps.

As a detailed specific example for practicing the present invention, the electrical circuit as shown in FIG. 1 will be considered and all voltages will be given with respect to the output terminal of the furnace 1, which is grounded. The tube V1 is a type 5669. The potential applied to the anode of the tube V1 is 2340 volts above ground. The potential applied to the grid of tube V1 is 1460 volts above ground. The cathode of the tube V1 normally has applied thereto a potential of 1340 volts above ground. The non-linear resistor is formed of fifteen 150 watt, 125 volt conventional incandescent lamps, connected in series. Accordingly, the normal potential drop which occurs across these series-connected lamps is 1340 volts. The potential applied at the input terminal or cathode 5 of the electron beam zone refining furnace 1 is 3000 volts below ground. Any decrease in electrical resistance in the furnace 1 will increase the potential drop across the non-linear resistor. This in turn will be reflected as an increase in potential above ground as applied at the cathode of the tube V1 to limit the current drawn by the tube V1 and stabilize the current through the circuit. The normal current through the entire circuit is approximately 1 ampere. It will be seen that when an overload occurs, the cathode potential is moved in a positive fashion with respect to the predetermined potential which is applied to the grid of the tube V1 in order to control the current. It should be understood that the foregoing specific example has only been given by way of illustration and is subject to considerable modification.

While in accordance with the patent statutes, one best example has been illustrated and described in detail, it is to be particularly understood that the invention is not limited thereto or thereby.

I claim:

1. An electron-beam, zone-refining furnace and the electric power source therefor, said furnace comprising a cathode connected to a furnace electrical input terminal and an anode comprising the object being refined and connected to a furnace electrical output terminal, said furnace normally operating with a predetermined current passing therethrough, said electric power source comprising:

(a) electron power tube means having an anode, a cathode, and a control grid, said tube means during operation of said furnace acting to pass the operating current drawn by said furnace;

(b) first D.C. potential source means having an output potential of predetermined value and connected across the input terminals of said furnace and the anode of said tube means;

(c) second D.C. potential source means adapted to apply to the grid of said tube means a potential of predetermined value; and

(d) non-linear feedback impedance means connected in series between said tube means and said furnace, and said non-linear impedance means during normal operation of said furnace having a predetermined voltage drop thereacross and displaying a resistance which increases with increasing voltage drop thereacross.

2. An electron-beam, zone-refining furnace and the electric power source therefor, said furnace comprising a cathode connected to a furnace electrical input terminal and an anode comprising the object being refined and connected to a furnace electrical output terminal, said furnace normally operating with a predetermined current passing therethrough, said electric power source comprising:

(a) electron power tube means having an anode, a cathode, and a control grid, said tube means during operation of said furnace acting to pass the operating current drawn by said furnace;

(b) first D.C. potential source means having an output potential of predetermined value and connected across the input terminals of said furnace and the anode of said tube means;

(c) second D.C. potential source means adapted to apply to the grid of said tube means a potential of predetermined value; and

(d) non-linear impedance means connected between the output terminal of said furnace and the cathode of said tube means, and said non-linear impedance means during normal operation of said furnace having a predetermined voltage drop thereacross and displaying a curve of voltage drop thereacross versus current therethrough which has a slope considerably greater than the slope of a similar curve taken for a linear resistor.

3. The combination as specified in claim 2, wherein said non-linear impedance comprises tungsten filamentary wire.

20 4. An electron-beam, zone-refining furnace and the electric power source therefor, said furnace comprising a cathode connected to a furnace electrical input terminal and an anode comprising the object being refined and connected to a furnace electrical output terminal, said furnace normally operating with a predetermined current passing therethrough, said electric power source comprising:

(a) a plurality of electron power tube means each having an anode, a cathode, and a control grid, said tube means during operation of said furnace acting to pass the operating current drawn by said furnace, and the anode of the first of said tube means connected to the cathode of the next succeeding of said tube means;

(b) first D.C. potential source means having an output potential of predetermined value and connected across the input terminals of said furnace and the anode of the last of said tube means;

(c) second D.C. potential source means adapted to apply to the grid of each of said tube means electric potential of predetermined value; and

(d) non-linear impedance means connected between the output terminal of said furnace and the cathode of the first of said tube means, and said non-linear impedance means during normal operation of said furnace having a predetermined voltage drop thereacross and displaying a curve of voltage drop thereacross versus current therethrough which has a slope considerably greater than the slope of a similar curve taken for a linear resistor.

5. An electron-beam, zone-refining furnace and the electric power source therefor, said furnace comprising a cathode connected to a furnace electrical input terminal and an anode comprising the object being refined and connected to a furnace electrical output terminal, said furnace normally operating with a predetermined current passing therethrough, said electric power source comprising:

(a) first electron power tube means having an anode, a cathode, and a control grid;

(b) power amplifier electron tube means having an anode, a cathode, and a control grid, the anode of said first tube means connected to the cathode of said amplifier tube means;

(c) first D.C. potential source means having an output potential of predetermined value and connected across the input terminals of said furnace and the anode of said amplifier tube means;

(d) other D.C. potential source means adapted to apply bias excitation to the grids of all said tube means; and

(e) non-linear impedance means connected between the output terminal of said furnace and the cathode of said first tube means, and said non-linear impedance means during normal operation of said furnace having a predetermined voltage drop there-

across and displaying a curve of voltage drop thereacross versus current therethrough which has a slope considerably greater than the slope of a similar curve taken for a linear resistor.
